(57) **CLAIM**

The ornamental design for a handheld weighing scale, as shown and described.

DESCRIPTION

FIG. 1 is a top rear perspective view of a handheld weighing scale of our design;

FIG. 2 top front perspective view of the handheld weighing scale;

FIG. 3 is a rear elevation view of the handheld weighing scale;

FIG. 4 is a right side elevation view of the handheld weighing scale;

FIG. 5 is a top view of the handheld weighing scale;

(Continued)

FIG. 6 is a front elevation view of the handheld weighing scale; and,
FIG. 7 is a left side elevation view of the handheld weighing scale.

The dash-dash-dash broken line showing is included for the purpose of illustrating portions of the article that form no part of the claim.

1 Claim, 7 Drawing Sheets
